Primary Examiner — Sandra Morris(74) *Attorney, Agent, or Firm* — Keusey & Associates, P.C.(57) **CLAIM**

The ornamental design for a battery case with hinged cover and external jacks, as shown and described.

DESCRIPTION

FIG. 1 is a top, front, right side perspective view of our new design of a battery case with hinged cover and external jacks with the lid closed.

FIG. 2 is a top plan view thereof.

FIG. 3 is a front side elevational view thereof.

FIG. 4 is a right side elevational view thereof.

FIG. 5 is a back side elevational view thereof.

FIG. 6 is a left side elevational view thereof.

FIG. 7 is a bottom plan view thereof.

FIG. 8 is a top, front, right side perspective view of our new design of a battery case with hinged cover and external jacks with the lid open.

FIG. 9 is a top plan view thereof.

FIG. 10 is a front side elevational view thereof.

FIG. 11 is a right side elevational view thereof.

FIG. 12 is a back side elevational view thereof.

FIG. 13 is a left side elevational view thereof; and,

FIG. 14 is a bottom plan view thereof.
